SINE BAR

Albert H. Sheriff, Covington, Ky.

Application April 21, 1950, Serial No. 157,298

3 Claims. (Cl. 33—115)

1

This invention relates to a sine bar which is, generally speaking, a precision instrument used by tool and die makers for measuring and setting up angles with great accuracy. Since the uses of a sine bar are well known to one skilled in the art they will not be set forth in detail herein.

An object of the present invention is to provide a sine bar which is more universal than sine bars heretofore available and to provide a sine bar which can be used in a variety of positions with equal accuracy. It is another object of the invention to provide a sine bar which is capable of extremely accurate and delicate adjustment and which can be tightly clamped in any desired position of adjustment without affecting the adjustment thereof.

The advantages above set forth and others which will be set forth hereinafter or which will become apparent to the man skilled in the art upon reading these specifications I accomplish by that certain construction and arrangement of parts of which I shall now describe an exemplary embodiment.

Reference is made to the drawings forming a part hereof and in which:

Figure 1 is a plan view of a sine bar according to my invention.

Figure 2 is a front elevational view of the same.

Figure 3 is an end elevational view of the same.

Figure 4 is a cross sectional view on an enlarged scale taken on the line 4—4 of Figure 1.

Figure 5 is a view similar to Figure 4 but showing the parts in exploded condition.

Figure 6 is a fragmentary perspective view of the outer end of the blade showing a spacing block which may be used.

Briefly, in the practice of my invention I provide a basic block and a blade pivoted thereto. The block will be accurately machined on all sides and will have a semi-circular end. A blade member will be pivoted on the center of the semi-circle at the semi-circular end, and the blade will be of exactly the same width as the basic block and therefore of the same width as the diameter of the semi-circle. The blade will have secured to it at a definite distance from the pivot point a disc which will be of a diameter equal to the width of the blade. This structure is well known in sine bars. The present invention relates to improvements in specific details of structure, as will now be set forth.

In Figure 1 the basic block is indicated at 10. It is machined so that its edges are all square with respect to each other and so that its opposite sides are parallel. At one end it will termi-

nate in a semi-circular configuration, as shown in Figures 1, 2 and 3 at 11. The semi-circle 11 will be drawn about the point 12 (Figure 1) so that the diameter of the semi-circular portion 11 will be exactly equal to the width of the block 10. Pivoted secured to the block 10 is a blade 13 which is of a width exactly equal to the width of the block 10 and therefore also equal to the diameter of the semi-circular portion 11. The point 12 mentioned above is the pivot point of the blade 13 with respect to the block 10. The blade 13 carries at an accurately determined distance from the point 12 a disc 14, which disc is also of a diameter exactly equal to the width of the blade 13. The distance between the pivot point 12 and the center 15 of the disc 14 is some accurately measured distance such as, for example, ten inches. Ten inches is a desirable value because it facilitates the use of this device with a table of sines.

Referring now in more detail to Figures 4 and 5, I shall describe the manner of assembling the block 10 and the blade 13. The block 10 is provided with a hole 20 having a keyway 21 and a counterbore at 22. The blade 13 is provided with a hole 23 of the same diameter as the hole 20 and a washer 24 is arranged between the block 10 and the blade 13. The washer 24 also has a hole 25 of the same diameter. A knurled disc 26 is provided with a hole 27 of the same diameter which is counterbored as at 28. The disc 26 is provided with spanner holes at 29. The parts thus far described are held in assembled relation by cooperation between the threaded stud 30 and the nut 31. The stud 30 has a shank 30a of a diameter to fit snugly the holes 20, 23, 25 and 27, and it is provided with a key 32 arranged to engage in the keyway 21; but the key 32 is spaced from the flange 33 of the stud so that, as best seen in Figure 4, the key 32 engages in the keyway 21 of the member 10 and clears the washer 24.

The nut 31 has a central boss 34 of a diameter to fit the bore 20 and is internally threaded at 35 for engagement with the threads 36 of the stud 30. The main diameter of the nut 31 is such as to fit snugly within the counterbore 22, and the thickness of the nut 31 is such that it fits flush with the surface of the block 10. Similarly the flange 33 fits flush within the counterbore 28.

By virtue of the construction described the nut 31 may be tightened without disturbing the setting of the blade 13 with respect to the block 10. A spanner wrench is provided as shown in broken lines at 37 in Figure 5 and has the studs 38 which may be engaged in the spanner holes 39 in the

nut 31 or in the spanner holes 29 of the knurled disc 26. The engagement between the key 32 and the keyway 21 effectively prevents relative rotational movement between the stud 30 and the block 10. Thus, when the nut 31 is tightened, the stud 30 is simply drawn into the block 10 longitudinally and with no twisting movement. Therefore the disc 26 simply exerts pressure against the blade 13 and through the washer 24 against the block 10 without disturbing any angular setting which may have been made.

To facilitate quick setting the blade 13 may be provided with an index 40 (Figure 3) and the semi-circular portion of the block 10 may be provided with markings 41 which may be in degrees if desired so that a preliminary rough setting may be made by simply aligning the index 40 with the suitable graduations on the scale 41. The graduations on the scale 41 will run both ways from a zero position so that angles in either direction may be set up. The nut 31 may then be partially tightened and fine adjustment may be accomplished by movement of the knurled disc 26 which is in frictional engagement with the blade 13. If the clamping action is fairly tight, and a minute adjustment is desired, the spanner wrench 37 may be applied to the knurled disc 26 and in this way very minute adjustments of the blade 13 with respect to the block 10 may be made. When the desired angle has been set up, as by the use of a gauge block in connection with the disc 14 and a reference surface upon which the block 10 rests, the nut 31 is finally tightened and will hold the parts firmly in the desired position.

Since all surfaces of the block 10 and the blade 13 have been accurately machined, the sine bar according to the present invention may be used in any position. It may even be used upside-down from the position shown in Figures 2 and 3, since the thickness of the disc 14 and the thickness of the knurled disc 26 are identical. However, it will generally be used either in the position shown in Figures 2 and 3 or in a position like that of Figure 1, if Figure 1 were an elevational view.

When the blade 13 is widely opened there will be an overbalancing tendency. In order to avoid this difficulty I provide a separate block in the nature of a foot and indicated in Figure 6 at 42. The block 42 is provided with a slot 43 having walls parallel to the end walls of the block 42, and the slot 43 will be exactly the thickness of the blade 13 and will be spaced from one end of the block 42 in the same way as the blade 13 is spaced from the bottom surface of the block 10, as seen in Figure 2. Thus, the slot 43 will be at a distance "a" from one end of the block, corresponding to the distance "a" as shown in Figure 2, so that if the device is used in the position of Figure 2, the block 42 may be slipped on as shown in Figure 6, and it will support the blade in its overhanging position. If the device is used in the upside-down position, the slot 43a will be used, and will be engaged with the block 10 which it fits snugly. In this case the slot 43a is spaced from one end of the block 42 by a distance "b" corresponding to the distance "b" as shown in Figure 2, so that the block 42 will support the block 10 horizontally. If desired, threaded holes may be provided in the block 42, and a thumb-screw 44

may be used to clamp the block to the blade 13 or the block 10.

In order that the sine bar of my invention may be used in a lathe or the like between centers, I have provided the center holes 50, 51 on the longitudinal centerline of the block 10.

I have not discussed the uses of the sine bar since the uses are well known to any tool and die maker. The advantages of the present tool will be obvious to those skilled in the art who will know how to use it without further instructions. It will be clear that numerous modifications may be made without departing from the spirit of my invention, and I therefore do not intend to limit myself, except as set forth in the claims which follow.

Having now fully described my invention, what I claim as new and desire to secure by Letters Patent is:

1. In a sine bar comprising a block and a blade, a pivoting and clamping assembly therefor comprising a thin washer between said block and blade in the pivoting area, a threaded stud and a nut, said blade and block having a hole to accommodate snugly said stud, key means for preventing relative rotation between said stud and said block, said block having a counterbore, said nut having a diameter and thickness to fit snugly and flush within said counterbore, and a knurled disc having a hole to accommodate snugly said stud, said disc having a counterbore and said stud having a flange of a diameter and thickness to seat snugly and flush within said last named counterbore, said disc bearing frictionally against said blade, and said nut bearing against said block.

2. The structure of claim 1, wherein said nut and said knurled disc are provided with spanner engaging abutments.

3. The structure of claim 1, wherein said nut has a portion of a diameter to extend snugly into the hole in said block.

ALBERT H. SHERIFF.
